MILLING MACHINE FOR COPYING OR
PROFILINGHarry Frederick Atkins, Old Fletton, Peter-
borough, EnglandApplication September 21, 1938, Serial No. 230,913
In Great Britain August 11, 1937

6 Claims. (Cl. 90—13.7)

The invention relates to a milling machine suitable for copying, profiling and like operations of that kind in which a slide carrying the work and a pattern having exactly the shape and size desired of the article to be manufactured is diametrically mounted upon the face of a carrier-head arranged for intermittent revolution at the end of each traverse of the slide relative to a milling cutter to operate on the work and in which a stylus or follower, which contacts the pattern, controls the movement of the cutter.

According to the invention a milling machine of the aforesaid kind is characterised in that the traverse of the slide is effected by hydraulic means automatically controlled through valve mechanism by the intermittent rotation of the carrier-head.

Further, according to the invention, said carrier-head is held from revolving by an automatic catch released by the completion of the traverse of the slide, whereupon the carrier-head automatically revolves, and the commencement of this revolution automatically shuts off the liquid pressure.

According to constructional and functional features of the invention, the hydraulic means embodies either a single cylinder, with its complementary double-acting piston, arranged within the carrier-head parallel with the slide, or two cylinders, and their complementary double-acting pistons, one on each side of the centre of the slide and parallel therewith, the ends of the cylinder or cylinders being provided with ducts to form inlet and exhaust passages. The pistons are suitably connected to the slide, preferably by a mechanism which multiplies the movement of the slide in relation to the movement of the piston or pistons, as for example, by a toothed pinion mounted to revolve upon a diametric pin of a piston and to engage two racks, one upon the revolute head and the other at the slide. The valve mechanism upon the inlet side of the liquid pressure is preferably provided with a by-pass valve which is normally open but closes automatically, if any increased resistance is offered to machining the work, so that a greater liquid pressure is temporarily utilised to overcome the increased resistance, said liquid pressure with the by-pass valve open being normally calculated to normal machining resistance. The pressure-liquid supply and exhaust are arranged through the stationary frame of the machine to communicate with the back of the revolute carrier-head.

An embodiment of the invention in its desir-

able form is represented by the accompanying sheets of drawings.

Fig. 1 is a front elevation of the carrier-head and slide and other co-operative parts.

Fig. 2 is a horizontal section of Fig. 1.

Fig. 3 is an axial sectional elevation through the carrier-head, slide and stationary frame.

Fig. 4 is a detail section showing material parts of the valve mechanism.

Fig. 5 is a detail section of such valve mechanism at right-angles to Fig. 4.

The revolute carrier-head 1 is mounted by roller bearings 2, 3, upon the stationary frame of the machine, parts of which are represented at 4, to be revolved intermittently about the axis 15 of the carrier-head by operation of a worm 5 adapted to drive the worm-wheel periphery 6 of said carrier-head, said worm being conveniently driven by a friction drive, not shown.

A slide 7 is diametrically arranged upon the face of the carrier-head 1, and also within said head at the back of the slide are arranged two cylinders 8 and 9 having complementary double-acting pistons 10 and 11, said cylinders being parallel with the slide and one on each side of its centre line. Each piston is provided with a toothed pinion 12 mounted to revolve upon a diametric pin 13 disposed intermediate of the piston ends, each pinion gearing with opposed racks 14 and 15 carried, respectively, by the slide and the carrier-head, the operation of the slide from the cylinders and pistons being therefore balanced. The pinion and rack gears are such that the slide is traversed in ratio of two to one to the movement of the pistons 8 and 9.

At each of their ends the two cylinders communicate through ducts 16 and 17 with a liquid passage 18 controlled by valve action for both inlet and exhaust by the intermittent revolution of the carrier-head, as will be hereinafter described, these ducts 16, 17 and passages 18 alternately constituting inlet and exhaust.

Upon the carrier-head 1, there are provided two lugs 19 and 20 to co-operate with a pivoted catch 21 which normally holds the carrier-head 45 from revolution, this catch to be moved out of action by the completion of a traverse of the slide 7. For this purpose, the slide 7 is provided with two pegs 26, one of which, at the completion of each traverse of the slide, pushes against 50 an abutment 27 of the catch 21 and forces said catch out of engagement with the lug 19 or 20 on the carrier head. When the carrier head 1 has thus been freed, it revolves automatically a half-revolution until the other lug 19 is engaged.

by the catch. The slide 7 traverses always in the same direction after being turned round by the part-revolution of the carrier-head.

The driving gear for the worm 5 is in any suitable way instantly started and stopped by the release and engagement of the catch 21 with one of the lugs 19 and 20.

The work 22 and a pattern 23, having exactly the shape and size desired of the article to be manufactured, are coincidently carried centrally upon the slide, and the milling cutter 24 and a stylus or follower 25 operate against said work and pattern, respectively. The cutter 24 and stylus 25 are usually carried on a common movable arm (not shown), arranged for lifting and lowering movements only to follow the contours of the pattern.

It will be readily understood that the work 22, illustrated as a cycle crank, is machined between its semi-circular ends during the traverse of the slide 7, and is machined around its semi-circular ends by the half revolution of the carrier-head 1.

The construction and arrangement of the valve mechanism are illustrated in Figs. 4 and 5, the position of the parts being with the carrier-head 1 held from revolution and the slide in course of traverse.

Pressure liquid, such as from an accumulator, is supplied to the passage 28 provided within the stationary frame 4 to communicate by passages 29 and 30 with the passage 18 leading to the two ducts 16 and 17 of the cylinders 8 and 9. The passage 30 and part of the passage 29 are in a spring pressed plunger 31 carried by the frame 4, and the passage 18 is in a spring pressed plunger 32 carried by the carrier-head 1, and when these two plungers engage each other, as shown in Fig. 4, the passages 30 and 18 communicate, and the passages 29 are coincident, as also are passages 32a between the passage 18 and the ducts 16, 17, so that pressure liquid enters the cylinders 8 and 9 to operate the pistons and traverse the slide.

It will be clear that the spring pressed plunger 31 is carried by the stationary frame 4, and that the spring pressed plunger 32 is carried by the revoluble carrier-head 1, so that when the carrier-head automatically makes a part revolution the commencement of its movement instantly breaks connection between the passage 30 and 18, so that the spring pressed plungers 31 and 32 operate to close the passages 29 and 32a and therefore communication between the pressure liquid passage 28 and the cylinders, to thereby instantly stop traverse of the slide.

While liquid pressure is being supplied to the one ends of the cylinders the other ends of said cylinders are exhausting through one of the passages 18 to other suitable exhausting passages provided within the stationary frame 4. It follows from the aforesaid description that the hydraulic means is automatically controlled through suitable valve mechanism by the intermittent revolution of the carrier-head making and breaking the liquid joints between the passage 30 in the stationary frame and the passage 18 in the revoluble carrier-head.

It frequently happens in the milling of work, particularly when profiling, that resistance to the operation of the cutter temporarily increases, as for example, by a little harder metal being met with in the work. To provide for this contingency the pressure liquid supplied to the passage 28 is greater than normally needed for the work, involving a by-pass valve 33 being provided in

the stationary frame 4 to liberate the normal excessive pressure to an outlet 34 in said frame, this by-pass valve being normally spring pressed into open position, but adjusted to close onto its seating 35 only when the pressure at the passage 28 increases, i. e., greater resistance at the work, which will cause the valve 33 to automatically close and thereby increase the liquid pressure supplied into the cylinders 8 and 9 to overcome the temporarily increased work resistance which, on being removed, the by-pass valve 33 will again automatically reopen and the work proceed at normal liquid pressure.

The invention is applicable to a milling machine protected by my concurrent application Ser. No. 230,912 wherein the work and pattern are arranged to make swivelling or like movements additional to the movements of the slide and carrier-head.

Having now described my invention, what I claim and desire to secure by Letters Patent is:

1. In a milling machine of the kind described, the combination with a stationary frame, a revoluble carrier head, means to intermittently revolve said carrier head, a slide mounted transversely displaceable on said carrier head, and means to mount a pattern and the work on said slide, of hydraulic means to traverse said slide across said carrier head, and a valve mechanism to control said hydraulic means in dependence upon the intermittent revolutions of said carrier head.

2. A milling machine, as claimed in claim 1, in which said hydraulic means comprises a cylinder provided within the carrier-head parallel with the slide, a double acting piston slidable in said cylinder and connected with said slide, pressure liquid supply and exhaust ducts on said frame, ducts provided in the carrier-head at each end of the cylinder to form inlet and exhaust passages for pressure liquid, and valve mechanism provided between said ducts in the carrier head and said ducts on the stationary frame for automatically controlling the supply and discharge of pressure liquid to and from said cylinder in dependence upon intermittent revolution of the carrier head.

3. A milling machine, as claimed in claim 1, in which said hydraulic means comprises two cylinders provided within the carrier-head one on each side of the centre of the slide and both parallel therewith, two complementary double acting pistons slidable in said cylinders, respectively, and connected with said slide, pressure liquid supply and exhaust ducts on said frame, ducts provided in the carrier-head at each end of the cylinders to form inlet and exhaust passages for pressure liquid, and valve mechanism provided between said ducts in the carrier head and said ducts on the stationary frame for automatically controlling the supply and discharge of pressure liquid to and from said cylinders in dependence upon the intermittent revolution of the carrier head.

4. A milling machine as claimed in claim 1, in which said hydraulic means comprises a cylinder provided within the carrier-head parallel with the slide, a double-acting piston slidable in said cylinder, a toothed pinion mounted to revolve upon a diametric pin of said piston, racks on the carrier-head and slide, respectively, engaged by said pinion pressure liquid supply and exhaust ducts on said frame, ducts provided in the carrier-head at each end of the cylinders to

form inlet and exhaust passages for pressure liquid, and valve mechanism provided between said ducts in the carrier head and said ducts on the stationary frame for automatically controlling the supply and discharge of pressure liquid to and from said piston in dependence upon the intermittent revolution of the carrier head.

5. A milling machine, as claimed in claim 1, in which said valve mechanism includes a normally open by-pass valve adapted to close auto-

matically as increased resistance is offered to machining.

6. A milling machine as claimed in claim 1, wherein said valve mechanism includes two spring pressed plungers co-operating with each other when the carrier head is at rest and one of them with a back circular face of the carrier-head during the intermittent revolution of said head. 5
